United States Patent Office.

MILTON ALDEN, OF AUBURN, NEW YORK.

Letters Patent No. 76,480, dated April 7, 1868.

IMPROVEMENT IN HORSE-RAKES.

The Schedule referred to in these Letters Patent and making part of the same.

TO ALL WHOM IT MAY CONCERN:

Be it known that I, MILTON ALDEN, of the city of Auburn, in the county of Cayuga, and State of New York, have invented a new and useful Improvement for Fastening the Teeth in Horse-Rakes; and I do hereby declare that the following is a full, clear, and exact description of the same, reference being had to the accompanying drawing, forming part of this specification, in which—

Figure 1 is a side view of the tooth C passing through its compensating holder A, and secured by a transverse or longitudinal key B B, agreeably to the maker's pleasure.

Figure 2 is an illustration of the compensating holder A, with its transverse hook-pointed key B securing the tooth C in the holder A.

Figure 3 is a corresponding illustration to fig. 2, with this difference, viz, that it illustrates an end view of the key B securing the tooth C in the holder A; and

Figure 4 is a plan illustrating the holder A as used on a round rod, D, to allow the tooth C to adapt itself to any unevenness or irregularity of surface over which it may have to pass when in use.

Teeth in the horse-rakes heretofore constructed have been secured by means of set-screws, and require more material in the holders, which surplus is partially drilled out for the tooth to pass through, and for the set-screw hole above it, which, with the necessary tapping, forging, and screw-cutting, together with the requisite means for shifting the rake-teeth, when required, adds greatly to the first cost of the rake, and a considerable inconvenience when in use. With my improved arrangement, all this inconvenience is avoided, for, by the use of any substance at hand, whereby a slight blow may be given, the key B releases the tooth C, enabling the attendant to adjust any or all the teeth at pleasure, while, by the set-screw pin device, a suitable screw-wrench is requisite to turn these set-screws, which, from necessity, are small, and are frequently broken or twisted off, or their threads are stripped, causing delay when most required, sometimes nearly equivalent to the rake's value. But, by my arrangement, these delays and inconveniences are provided against, as the keys cannot well be broken, neither lost, as the hook at their point prevents their coming out so long as the teeth are in place.

Having thus fully described my invention, what I claim therein as new, and desire to secure by Letters Patent, is—

The keys B, in combination with the tooth C and the holder A, as set forth for the purposes described, whether used transversely, longitudinally, or otherwise, for said purpose.

MILTON ALDEN.
